UNITED STATES PATENT OFFICE.

LEOPOLD GUGGENBERGER, OF HASTINGS-ON-HUDSON, NEW YORK, ASSIGNOR, BY DIRECT AND MESNE ASSIGNMENTS, TO ROLUP SCREEN COMPANY, OF NEW YORK, N. Y.

EDGE REINFORCEMENT FOR SCREENS AND THE LIKE.

Application filed December 30, 1921. Serial No. 526,056.

To all whom it may concern:

Be it known that I, LEOPOLD GUGGENBERGER, a citizen of the United States, and a resident of Hastings-on-Hudson, Westchester County, New York, have invented a new and useful Improvement in Edge Reinforcements for Screens and the like, of which the following is a full, clear, and exact description.

10 My invention relates to improvements in reinforcing attachments for wire screens, window shades, and similar structures which are operated in a window or similar opening, and which are rolled up or slide in the 15 said opening. An objection to rolling screens has been that they are so likely to get wrinkled or distorted on one or both sides near the edges, and once this occurs, the screens never get back to their flat 20 smooth shape. The same difficulty is had in curtains or shades, particularly shades for car windows, in which the edges of the shades run in guide slots. The shades are inclined to blow out or get out of place by 25 rough usage, and it is difficult to get them back in place. Moreover, the flapping of the shade is apt to distort it and be objectionable generally. The object of my invention is to overcome these difficulties, 30 and to produce an attachment which is simple and inexpensive, and can be easily applied to the edges of the screen, shade, or the like, so that the material to which the attachment is applied will wear much longer, 35 and will be generally better for the purpose intended. In carrying out this idea I employ a strip of thin metal at each edge longitudinally of the material to which it is applied, and apply the strip in such a way 40 that it will not add materially to the bulk of the screen, shade, or article to which it is applied. This metal strip should be sufficiently springy to retain its shape, but capable of being easily rolled up with the 45 screen or shade to which it is applied. It can be of any desired width according to the use to which the article is to be put, and when applied, it serves not only to keep the screen or shade in shape, but to 50 finish the raw edge which might otherwise occur, and as the strip adds a finish to the article, it obviates the necessity of otherwise finishing the edge, so that it serves the double purpose of an edge finish and

reenforcement. This will be better understood from the following description.

Reference is to be had to the accompanying drawings forming a part of this specification, in which similar reference characters indicate corresponding part in all the 60 views.

Figure 1 is a broken front view of a window frame having a screen therein provided with my improvements.

Figure 2 is a vertical section thereof.

Figure 3 is an enlarged broken front view of one part of a screen fitted with my reenforcement.

Figure 4 is a view similar to Figure 3, but showing a slightly modified form of 70 fastening clip.

Figure 5 is a view of a partially opened clip for fastening the edge reenforcement to the screen or shade, and

Figure 6 is a detail sectional plan showing how the structure illustrated in Figure 4 is used.

By way of example I have shown my invention applied to the edges of the screen 10, but obviously this screen can be any 80 flexible material such as would be used in a window frame or the like, whether metallic, woven, textile, or other fabric. The manner in which the screen or shade operates is not material, but I have shown the 85 screen running on a roller 11 at the top of a window, and sliding in slots in a window frame 12. Structures of this kind usually enter slots in a window frame for 90 guiding purposes.

In the drawings I have shown metallic fastening strips 13 of thin sheet spring metal running along the edges of the screen 10, and these are sufficiently springy to retain their shape, and if they are fastened 95 securely to the adjacent material, they will obviously keep the material from kinking, twisting, or getting out of shape.

It is evident that the reinforcing strips might be fastened to the edges of the material in very many ways without affecting the invention. I have shown a convenient way in which metallic clips 14 are used, these being doubled in the middle as shown at 15 so as to embrace the strips 13, and 100 each clip has laterally projecting points 16, one member of which can be passed through the material of the screen or the like and

doubled over upon the other member of the clip, as clearly shown in the drawings. The metal of the clips 14 is soft enough to bend without breaking, and so the clips can 5 easily clasp in the middle portion the edge strip 13, the opposed members of the clips being then pressed firmly against the web of the screen or shade. The members 16 can be turned up so that they will pierce 10 the web, and their free ends can be doubled over and pressed down upon the second member of the clip so that the two members of the clip are firmly fastened together with the strip 13 and the web of the screen 15 between them.

In some cases it is desirable to have the edges of the screen, shade, or the like engage a guide which will prevent the displacement of the article. With my invention 20 this is not necessary, as the reinforcing metallic strips 13 of springy material serve to keep the article to which they are attached taut and straight, and so the article can run in a plain slot or groove without much 25 danger of displacement; but if desired the screen or shade can be made to engage a device to keep it in place as well as if the fastening strips were not used. A convenient way of accomplishing this result is 30 to have the clips 17 like those already described but slightly longer, so that the outwardly projecting part may be doubled over laterally to form a hook 18 which can slide behind a suitable guide 19 as in Figure 6. 35 No attempt is made to illustrate any necessary form of guide, but the illustration makes it clear that the fastening clips can be used to prevent the displacement of the shade or screen to which they are attached, 40 and it is obvious that the projecting clips can be bent to any desired shape so as to fit any preferred form of guide. It will be further observed that as the clips are spaced apart and are narrow, they will not interfere 45 with the rolling up of the article to which they are attached, but will serve to bind the article firmly to the reinforcing edge strips 13.

These reinforcing strips have been thoroughly tried out, and it is found that they serve perfectly to keep the article to which they are attached taut and straight, and to provide against its being twisted or bent out of shape, and that they further serve to keep 55 the article of which they form a part in its guide slots.

In the claims I have referred to my improved reinforcement as applied to screens,

but it will be obvious that it can be applied to any other similar flexible member, such as 60 a shade or the like.

I claim:—

1. As an improved article of manufacture, a screen, comprising a body portion, thin flexible metallic strips at the side edges of 65 the body and substantially in the plane of the body, said strips and body portion being placed edge to edge, and fastening clips overlapping a substantial part of both sides of the body to which they are secured and 70 engaging the strips, with the outer portions of said clips bent laterally to form guiding devices.

2. As an improved article of manufacture, a screen, comprising a body, thin flexible 75 springy metallic strips at the side edges of the body and substantially in the plane of the body, said strips and body portion being placed edge to edge, and fastening clips overlapping a substantial portion of both 80 sides of the body and clamped thereto, said clips embracing the aforesaid metallic strips and having their outer portions formed into guiding devices.

3. As an improved article of manufacture, a screen, shade, or the like, comprising a substantially conventional body portion, thin, flexible metallic springy strips at the side edges of the body, and in substantially 90 the same plane as the body, the strips and body being arranged edge to edge, and fastening clips embracing the strips and overlapping a substantial portion of both sides of the body to which they are attached.

4. A screen, comprising a substantially conventional body portion, thin flexible springy metallic strips at the side edges of the body, the strips and body being arranged edge to edge, and members fastening the strips to the body and projecting from the outer edges 100 of the strips to engage complementary guiding devices.

5. A screen, comprising a substantially conventional body, reinforcing edge strips at the sides of the body, said strips being 105 arranged edge to edge with the body, and said strips also being formed of thin springy metal, and fastening clips embracing the strips and engaging the body, said clips being prolonged at their outer extremities to 110 form guiding devices.

LEOPOLD GUGGENBERGER.
